UNITED STATES PATENT OFFICE.

FRANK A. PETERS, OF CHICAGO, ILLINOIS.

WINDOW-DRAPERY-HANGER DEVICE.

Application filed May 14, 1920. Serial No. 381,324.

To all whom it may concern:

Be it known that I, FRANK A. PETERS, a citizen of the United States, and a resident of the city of Chicago, in the county of Cook and State of Illinois, have invented certain new and useful Improvements in a Window-Drapery-Hanger Device; and I do hereby declare that the following is a full, clear, and exact description of the same, reference 10 being had to the accompanying drawings, and to the numerals of reference marked thereon, which form a part of this specification.

This invention relates to drapery hangers 15 and is particularly adapted for use with window curtains and draperies. The subject of this invention constitutes improvements upon a prior patent granted to applicant, No. 1,327,961, issued January 13, 20 1920.

Hitherto in changing window curtains it has been necessary to ascend a stepladder which was accomplished with more or less danger and trouble.

25 Also, in washing or cleaning windows it has heretofore been necessary to either throw back and support the window curtains, or draperies, or to remove them entirely.

30 One of the principal objects of this invention is to provide means whereby curtains can be replaced without the use of a ladder.

Another object of the invention is to provide a method of supporting the curtains 25 while cleaning the windows, so as not to interfere with the work of cleaning and also so that the curtains will not be soiled.

Still another object of the invention is to provide means whereby free access may be had to the window for any purpose without disarranging or rumpling the curtains.

A further object of this invention is to provide means whereby the window may be opened at any time for purposes of ventilation without danger of snow, soot or the like blowing upon the curtain.

Still another object of the invention is to provide a hanger whereby the curtain thereon may be partly lowered to admit air and light.

Other and further important objects of this invention will be apparent from the disclosures in the specification and drawings.

The invention (in a preferred form) is 55 illustrated in the drawings and hereinafter more fully described.

On the drawings—

Fig. 1 is an interior view of a window having a lace curtain and draperies applied thereto by means of my device. 60

Fig. 2 is a similar view showing the hanger with the curtains removed therefrom.

Fig. 3 is an elevation of the main portions of the hanger and its adjusting devices, 65 parts being broken away.

Fig. 4 is a top plan view of the horizontal portion of the hanger.

Fig. 5 is a section on the line 5—5 of Fig. 3, showing the improved wedge. 70

Fig. 6 is a section on the line 6—6 of Fig. 4 showing the releasable clamp.

Fig. 7 is a section on the line 7—7 of Fig. 4, showing the vertical guiding means.

Fig. 8 is a section on the line 8—8 of Fig. 75 4, showing the telescoping members.

Fig. 9 is a section on the line 9—9 of Fig. 4.

Fig. 10 is a sectional view showing the means of retaining the telescoping sections 80 in position.

Fig. 11 is a section on the line 11—11 of Fig. 4 looking in the direction indicated by the arrows.

As shown on the drawings—

The reference numeral 12 indicates a vertically slidable and horizontally rotatable tube or rod having a handle 13 pivoted as shown at 14. This rod is supported by a bracket 15 secured to the side of the window frame. At the top of the tube or rod 90

12 is affixed a horizontal tube 17 bent in a right angle at 18. The tube 17 may be affixed to the tube 12 by telescoping them as shown in Fig. 7 or in any convenient 95 manner. The tube 17 preferably extends halfway across the window and is provided with a reinforcing ring 19 at its end. A set screw 20 is inserted through one side of the reinforcing ring 19 and the tube 17, as 100 shown in Fig. 8. A rod or tube 21 of a diameter to just fit inside the tube 17 is telescopically inserted in the end thereof, said rod 21 being bent at a right angle as at 22 (see Fig. 4). The end of the rod 21 is 105 tapered and fashioned as shown at 22, Figs.

4 and 6, to releasably engage a spring clip 23 which is fastened to the window frame at the top thereof by means of screws 24. The bracket 15 is secured to the window 110 frame by means of screws or nails 25 and supports a fixed vertical tube or rod 26 se-

cured at its upper end to the top of the window frame by a screw 27. The rod 26 is spaced from and parallel with the window frame.

5 At the upper end of the rod 12 is rotatably fixed a member 28 which is slideable on the rod 26. The rod 12 may turn freely in the member 28 but is prevented from sliding motion relative thereto by means of 10 cotter pins 29 or the like.

The bracket 15 is provided with a ledge 30 on which rests a lever 31 (see Fig. 5) having a hole therein for the passage of the rod 12. A spring 32 encircles the rod 12 15 and presses down on the lever 31 which grips the rod 12 thereby preventing any vertical motion thereof, unless the lever 31 is raised, but always allows a free horizontal turning motion of the rod 12 about its longitudinal axis.

The combination of the rods 17 and 21 is intended to support a set of draperies and an additional rod or tube is provided for the support of the lace curtain. This tube 25 is made in two sections 33 and 34, one fitting slidably within the other. The ends of these sections are flattened and bent as at 35 and 36 forming hooks by means of which the curtain holding tube is supported 30 on the drapery holding tube and is movable therewith, but removable therefrom. These hook members 35 and 36 also serve as means for retaining the draperies in position.

The operation is as follows:

35 Whenever, for any reason free access to the window is desired, the entire bracket with the curtains and draperies thereon can be swung away from the window in the manner of a door simply by grasping the 40 handle 13, turning same to a horizontal position and swinging the bracket around thereby, the end of the bar 21 pulling out

of the spring clip 23. The rod or tube 12 rotates freely in the member 28 and the lever 31 likewise allows of its free turning movement as this lever locks it against vertical movement only. The tapered end of the rod 21 in conjunction with the spring clip 23 holds the curtain against any accidental displacement, which might result 45 from wind pressure.

Whenever it is desired to replace the curtains or draperies the handle 13 is grasped, and the lever or wedge 31 lifted, releasing the rod 12 which may be then slide downwardly 50 to the dotted-line position shown in Fig. 2, where the curtains may be conveniently replaced or rearranged, by a person standing on the floor.

I am aware that numerous details of construction may be varied through a wide range without departing from the principles of this invention, and I therefore do not purpose limiting the patent granted otherwise than necessitated by the prior art. 55

I claim as my invention—

In a window drapery support, an upright, means slidably and rotatably securing said upright at one side of the window, a U-shaped cross piece secured to the upper end 70 of said upright and extending across the window with the open end of the U toward the window, a supplemental tubular cross piece connecting the arms of the U, said tubular cross piece having its ends collapsed 75 and formed to fit about the arms of the U, the closed end of the U and said cross piece being both telescopic.

In testimony whereof I have hereunto subscribed my name in the presence of a 80 subscribing witness.

FRANK A. PETERS.

Witness:

EARL M. HARDINE.
